Primary Examiner — Ricky Pham

(57) **CLAIM**

The ornamental design for a microwave cooking utensil, as shown and described.

DESCRIPTION

FIG. 1 is a first perspective view of a microwave cooking utensil showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The dash-dash broken lines shown in the drawings depict portions of the microwave cooking utensil that form no part of the claimed design. The dot-dash broken lines in FIGS. 2 and 9 illustrate the periphery of the enlarged views of the microwave cooking utensil and form no part of the claimed design.
